Primary Examiner — John Windmuller*Assistant Examiner* — John R Yeh(74) *Attorney, Agent, or Firm* — Ladas & Parry LLP**CLAIM**

The ornamental design for a clip, as shown and described.

DESCRIPTION

FIG. 1 is a top side perspective view of a clip showing our new design;

FIG. 2 is a bottom side perspective view thereof;

FIG. 3 is a front elevation view thereof;

FIG. 4 is a rear elevation view thereof;

FIG. 5 is a right side elevation view thereof;

FIG. 6 is a top plan view thereof;

FIG. 7 is a bottom plan view thereof;

FIG. 8 is a sectional view thereof, taken along line 8-8 in FIG. 5; and,

FIG. 9 is a reference view showing the environment in which the design is associated.

The broken lines shown in the drawings form no part of the claimed design. The dot-dash lines shown in the drawings represent boundaries of claimed and unclaimed portions of the claimed design.

1 Claim, 5 Drawing Sheets See application file for complete search history.
